UNITED STATES PATENT OFFICE

161,785

TELEBINOCULAR STEREOSCOPIC INSTRUMENT

Charles M. Pettingell, Meadville, Pa., assignor to
Keystone View Company, Meadville, Pa., a cor-
poration of Pennsylvania

Application May 20, 1950, Serial No. 10,067

Term of patent 14 years

(Cl. D57—1)

To all whom it may concern:

Be it known that I, Charles M. Pettingell, citizen of the United States, residing at Meadville, Crawford County, Pennsylvania, have invented a new, original, and ornamental Design for a Telebinocular Stereoscopic Instrument of which the following is a specification, reference being had to the accompanying drawing, forming part thereof.

Figure 1 is a front view of a telebinocular stereoscopic instrument, showing my new design.

Figure 2 is a side view looking from the right hand side of Figure 1 with parts broken away.

Figure 3 is a plan view of the stand separate from the instrument.

Fig. 4 is a top view of the instrument apart from the stand.

The side of the instrument opposite the side shown in Figure 2 has the same appearance as that shown in Figure 2 except for the operating knobs or handwheels shown therein.

I claim:

The ornamental design for a telebinocular stereoscopic instrument, as shown, and described.

CHARLES M. PETTINGELL.
